United States Patent Office

Des. 202,463
Patented Oct. 5, 1965

202,463
POWER OPERATED GOLF SHOE CLEANER
Lloyd H. Leonard, 14877 Valley Vista Blvd.,
Sherman Oaks, Calif.
Filed May 4, 1964, Ser. No. 79,779
Term of patent 14 years
(Cl. D9—2)

FIG. 1.

FIG. 4.

FIG. 3.

FIG. 2.

FIG. 1 is a perspective view of the power operated golf shoe cleaner, embodying my new design;

FIG. 2 is a view in rear elevation of the same;

FIG. 3 is a view in side elevation of the same.

FIG. 4 is a top plan view of the same.

The interior portions of the rear of the casing conform in configuration to the exterior portions thereof as indicated.

The broken lines indicating the rod and the electric cord are for illustrative purposes only, the cord being shown broken away for convenience of illustration.

I claim:

The ornamental design for a power operated golf shoe cleaner, as shown and described.
